CHARM BRACELET OR THE LIKE

Adolph Katz, Providence, R. I., assignor to Coro, Inc.,
New York, N. Y., a corporation of New York
Application April 20, 1955, Serial No. 35,611

Term of patent 7 years

(Cl. D45—17)

Fig. 4

Fig. 1 is a front elevational view of a charm bracelet or the like showing my new design.

Fig. 2 is an edge view of the charm element.

Fig. 3 is a rear elevational view of the charm element shown in Fig. 2.

Fig. 4 is a bottom plan view thereof.

The dominant feature of my design resides in the portion shown in solid lines.

I claim:

The ornamental design for a charm bracelet or the like, substantially as shown and described.
